SANITARY DEVICE

Stanislaw Jakala, Chicago, Ill.

Application August 26, 1936, Serial No. 98,026

2 Claims. (Cl. 128—294)

My invention relates to the treatment of diseases, and has among its objects and advantages the provision of an improved sanitary device designed for male use.

5 An object of my invention is to provide a sanitary device along the lines of the device illustrated in my Patent 1,982,520, issued November 27, 1934. In the instant case, the unit is made 10 of flexible material and constructed in such a manner as to facilitate the use of flexible material in the nature of rubber. The unit is molded as a single piece and the attaching element is so designed as to provide an efficient supporting function.

15 In the accompanying drawing:

Fig. 1 is a perspective view of my invention;

Fig. 2 is an end view;

Fig. 3 is a sectional view along the line 3—3 of Fig. 2;

20 Fig. 4 is a sectional view along the line 4—4 of Fig. 3; and

Fig. 5 is a sectional view along the line 5—5 of Fig. 3.

In the embodiment selected to illustrate my 25 invention, I make use of a receptacle or cup 10 having an open end 12 for the reception of the male organ. The cup 10 is molded of resilient material such as rubber and includes a loop 14 which embraces the male organ for connecting 30 purposes. The loop 14, when viewed according to Figs. 1 and 3, is arranged in slightly angular relation with the open end of the cup 10. The loop is molded integrally with the cup 10 at 16 and is additionally connected with the cup 35 through the medium of straps 18 which are molded integrally with the cup 10 and the loop 14.

In use, it is important that the organ be held 40 in spaced relation with the wall of the cup. To this end the inner wall includes a rib 20 spaced inwardly of the open end of the cup and in par-

allel relation therewith. A second rib 22 projects inwardly of the wall and is U-shaped when viewed according to Fig. 4 and has its ends connected with the rib 20 as at 24, in Fig. 5. The ribs 20 and 22 perform a spacing function for the 5 organ so that the discharge may flow freely into the cup. The ribs are molded integrally with the cup.

The device is molded in various sizes. Because 10 of the straps 18, the loop 14 is effectively connected with the cup. In addition to supporting the loop 14 in proper angular relation with the cup, the straps 18 perform a reenforcing function with respect to the connection between the loop and the cup.

15 While the cup is of a flexible nature, the ribs 20 and 22 are of sufficient proportions and rigidity to constitute effective spacers. Because of the unit construction, the device may be manufactured at a low cost and its flexible nature embodies an element of accommodation to the organ.

Without further elaboration, the foregoing will 20 fully explain my invention, that others may by applying current knowledge readily adapt the same for use under various conditions of service.

25 I claim:

1. A device of the type described comprising a flexible cup, a flexible loop connected with the cup and positioned exteriorly thereof, flexible connecting straps between the loop and the cup, 30 and spacing elements positioned inside the cup and molded integrally therewith, said loop and said straps being molded integrally with the cup.

2. A device of the type described comprising a flexible cup having an open end, a flexible loop 35 connected with the cup in spaced relation with the open end, flexible straps connecting the loop with the cup, and flexible spacing ribs projecting inwardly of the cup wall.

STANISLAW JAKALA. 40
